(57) CLAIM

The ornamental design for a miniature steamboat memento, as shown and described.

DESCRIPTION

FIG. 1 is a top-right-rear perspective view of my miniature steamboat memento showing my new design;

FIG. 2 is a top-left-front perspective view of the miniature steamboat memento thereof;

FIG. 3 is a bottom-right-rear perspective view of the miniature steamboat memento thereof;

FIG. 4 is a bottom-left-front perspective view of the miniature steamboat memento thereof;

FIG. 5 is a top view of the miniature steamboat memento thereof;

FIG. 6 is a bottom view of the miniature steamboat memento thereof;

FIG. 7 is a left-side view of the miniature steamboat memento thereof;

FIG. 8 is a rear view of the miniature steamboat memento thereof;

FIG. 9 is a front view of the miniature steamboat memento thereof; and,

FIG. 10 is a right-side view of the miniature steamboat memento thereof.

The miniature steamboat memento (“miniature steamboat”) is characterized by various parts including a paddle wheel assembly, a wheelhouse, dual smokestacks, a base, a primary deck, a secondary deck, a top deck.

1 Claim, 10 Drawing Sheets
